UNITED STATES PATENT OFFICE.

FRANK JAMES KORTE, OF ZANESVILLE, OHIO.

FEED-WATER HEATER.

SPECIFICATION forming part of Letters Patent No. 293,889, dated February 19, 1884.

Application filed September 25, 1883. (No model.)

To all whom it may concern:

Be it known that I, FRANK JAMES KORTE, of Zanesville, county of Muskingum, State of Ohio, have invented a new and useful Improvement in Feed-Water Heaters; and I declare the following to be a full, clear, and exact description of the same, such as will enable others skilled in the art to which it pertains to make and use it, reference being had to the accompanying drawings, which form a part of this specification.

My invention consists in the combinations of devices and appliances hereinafter specified, and more particularly pointed out in the claims.

In the drawings, Figure 1 is a perspective view of a boiler embodying my invention. Fig. 2 is a longitudinal sectional view, showing a modification of the invention. Fig. 3 is a longitudinal section. Fig. 4 is a separate view of the feed-water heater. Fig. 5 is a sectional view of Fig. 1.

It is the object of my invention to construct a feed-water heater in sizes suitable for insertion within the smoke-box at the end of the boiler adjacent to the smoke-stack or uptake, so as to be heated with the waste heat of the products of combustion as they escape from the boiler flues or tubes and are about to pass to the chimney-flue.

My invention also has for its object the construction of this feed-water heater so that it shall swing out upon a hinge, the same as the ordinary door located at this point, so as to give ready access to the boiler flues or tubes, in case it is desired to get at them for cleaning or repairs.

In the accompanying drawings, which are designed simply to illustrate my invention, A is an ordinary horizontal boiler. B is the furnace; A', the boiler flues or tubes. C is the smoke-box; D, the chimney or uptake.

E represents my improved feed-water heater. It is of such size and dimensions as to fit within the end of the smoke-box, although, instead of fitting within the end, it may be adapted so as to fit against the end. It is provided with two or more interior partitions, E'. Two are represented in the drawings, and they divide the interior spaces into three chambers.

e is the inlet for the feed-water. e' is the mud-valve or blow-off, and e'' the exit for the feed-water. The middle space is represented as filled with hay, straw, excelsior, or their equivalent filtering material.

The operation of the device is obvious. Feed-water entering at e is heated by the waste heat of the products of combustion as they escape from the boiler-flues and before passing to the chimney. Being heated, the water deposits the main portion of its sediment in the lower chamber adjacent to the blow-off e'. Its remaining impurities and crystallizable salts are extracted in passing through the filtering-chamber and the space beyond it, and the water is discharged in a purified and heated condition from the exit e'', whence it is pumped into the boiler.

E² is a hinge by which the heater is suspended in its place, thus making the heater to serve the purpose of a door for gaining ready access to the boiler flues or tubes. The heater may be provided with man-holes E³, opposite any or all of its interior chambers, to facilitate the cleansing of the interior or renewal of the filtering material.

I would have it understood that I do not limit myself to a construction in which the heater is hinged to the smoke-box, for it may be simply inserted within or upon the end of the smoke-box, and be secured in any convenient way. The inlet or exit pipes for the water may be united with the heater by flexible pipes or couplings, so as to admit of opening the door without disconnecting the pipes; or they may be rigidly connected, in which case they would have to be unjointed before opening the heater from the end of the smoke-box.

It is my purpose to construct these heaters of different sizes, corresponding with the different sizes of standard boilers, so that they can be sold in such shape as to be immediately connected with any of the usual sizes of boilers. I purpose to make them of cast metal in a single piece, or to make them of wrought metal in parts riveted together, as may be deemed desirable, or cast steel, brass, or any metal.

This heater may, if preferred, be extended upward through the base of the smoke-stack,

and include said base of the stack within it, as illustrated in the modification shown in Fig. 2, so as to form a part of said stack, said heater being joined to the stack at the top by a suitable joint, the smoke passing through the upper part of the heater.

What I claim is—

1. The combination, with a boiler smoke-box, of a feed-water heater secured thereto, and composed of the chamber having partitions E', a filtering material arranged between the partitions, the inlet-port e, outlet-port e², and blow-off port e', substantially as and for the purposes described.
- 15 2. The combination, with a boiler, of a feed-water heater consisting of a chamber constructed to constitute a wall of the smoke-box, said heater hinged to the boiler at this point and serving as a door for gaining access to the tubes and flue, substantially as described.

3. The feed-water heater herein described, consisting of a chamber provided with partitions E', filtering material, and inlet and outlet ports, said heater constructed to fit within the boiler smoke-box and hinged to the boiler 25 at this point, substantially as described.

4. The combination, with a boiler, of a feed-water heater consisting of a chamber constructed to constitute a wall of the smoke-box, said heater extended upward around the base 30 of the smoke-stack and forming a part of said stack, substantially as described.

In testimony whereof I sign this specification in the presence of two witnesses.

FRANK JAMES KORTE.
